(57) **CLAIM**

The ornamental design for a trailer hitch storage mechanism, as shown and described.

DESCRIPTION

FIG. 1 is a perspective view of a trailer hitch storage mechanism;

FIG. 2 is a front view of the trailer hitch storage mechanism;

FIG. 3 is a rear view thereof;

FIG. 4 is a top view thereof;

FIG. 5 is a bottom view thereof;

FIG. 6 is a right side view thereof;

FIG. 7 is a left side view thereof; and,

FIG. 8 is a perspective view of the trailer hitch storage mechanism.

The broken lines depict environment that form no part of the claimed design.
